UNITED STATES PATENT OFFICE.

THEODORE C. MUNGER, OF CEDAR RAPIDS, IOWA, ASSIGNOR OF ONE-HALF
TO LESTER M. RICH, OF SAME PLACE.

PUMP-BUCKET.

SPECIFICATION forming part of Letters Patent No. 284,048, dated August 28, 1883.

Application filed April 7, 1883. (No model.)

To all whom it may concern:

Be it known that I, THEODORE C. MUNGER, a citizen of the United States, residing at Cedar Rapids, in the county of Linn and State of Iowa, have invented certain new and useful 5 Improvements in Pump-Buckets, of which the following is a specification, reference being had therein to the accompanying drawing.

This invention relates to certain improvements in pump-buckets; and it has for its objects to provide a bucket which will be simple and inexpensive in construction, which can be easily repaired, and which will not expand or contract or otherwise lose its shape while in 15 use.

The above-mentioned objects I attain by the means illustrated in the accompanying drawing, in which is represented a vertical sectional view of a pump-bucket constructed according to my invention.

In the drawing, the letter A indicates the body of my pump-bucket, which is constructed of wood or other non-metallic material of frustum shape, and provided with a central vertical aperture. The upper outer edge of the said body is rabbeted annularly, forming a seat for the flanged annulus B.

The letter C indicates a flanged annulus, within which the lower portion of the body of the bucket sets. The outer edge of the said lower annulus is about the thickness of the leather packing to be secured to the outside of the bucket. These annuli are preferably constructed of metal, and are provided with 30 apertures C', through which the clamping-bolts D pass, the body of the bucket being provided with corresponding apertures, E, for the pas-

sage of said bolts. The bolts are curved at their upper ends and provided with shanks F, between which is secured the lower end of the 40 pump-rod G by means of the transverse bolts H. The upper and lower annuli are clamped to the frustum-shaped body of the bucket by means of the nuts I, secured to the lower ends of the vertical bolts D. The portion of the 45 body of the bucket on the outside forms a seat for the packing K, which is secured to such exposed portion of the body by means of nails or other fastening devices, which are driven into the wood. The upper annulus, if found 50 necessary, may be provided with openings through its flange, through which nails or fastening devices may be driven, if required, to further secure the packing. The valve of the bucket is secured to the body in the usual 55 place.

Having thus described my invention, what I claim, and desire to secure by Letters Patent, is—

A pump-bucket consisting of a hollow non-metallic frustum, A, having an oblique rabbet at its upper edge, an upper confining-annulus, C', having an oblique flange, and a lower annulus, C, a packing secured to the outside of the non-metallic portion; and the bifurcated 60 extensions of the pump-rod, and the confining-screws, all arranged substantially as and for the purposes specified.

In testimony whereof I affix my signature in presence of two witnesses.

THEODORE C. MUNGER.
